UNITED STATES PATENT OFFICE.

GARDNER A. BELKNAP, OF CONNEAUTVILLE, PENNSYLVANIA.

RAIL TIE AND FASTENER.

996,306.

Specification of Letters Patent. Patented June 27, 1911.

Application filed January 3, 1911. Serial No. 600,580.

To all whom it may concern:

Be it known that I, GARDNER A. BELKNAP, a citizen of the United States, residing at Conneautville, in the county of Crawford 5 and State of Pennsylvania, have invented certain new and useful Improvements in Rail Ties and Fasteners, of which the following is a specification.

My invention relates to rail ties of the 10 composition type and fastening means for securing the rail thereto and has for one of its objects the provision of an improved construction of tie whereby an enlarged bearing surface is provided under the rails 15 by forming the tie wider under the rails, the widened portion being formed with slots to receive bolts that engage the clamping plates, said structure making it possible to renew broken or defective bolts while the tie 20 and rails remain in place.

My invention also has for its object the provision of a reinforcing rod for the tie that extends through the tie longitudinally and provided with threaded ends to receive 25 nuts to be tightened on the rod after the tie has dried and seasoned to hold the tie together securely and forming a truss to prevent it from cracking transversely.

My invention further has for its object 30 the provision of an improved rail clamping means embodying adjustable holding members secured by the bolts aforesaid and a rectangular washer mounted on each bolt and engaging a shoulder on the holding member, 35 the bolt hole in the washer being arranged at different distances from each side of the washer so that the clamping members may be adjusted to counteract the wear on the inner sides of the rails from engaging the 40 flanges of car wheels.

My invention will be described in detail hereinafter and illustrated in the accompanying drawings in which—

Figure 1 is a top plan view partly in section of my improved tie, Fig. 2, a side view, Fig. 3, a detail view of one of the clamping members, and Fig. 4, a detail view of one of the rectangular washers.

In the drawings similar reference characters indicate corresponding parts in all of the views.

My improved tie 1 is made of concrete or other suitable plastic material and is provided with a reinforcing rod 2 that extends 55 through the tie from end to end and has a threaded end extending beyond each end of

the tie on which threaded ends are mounted nuts 3 and washers 4. In making my tie, after it has dried and seasoned, the nuts 3 are screwed up on the rod 2 causing the rod 60 to act as a truss to prevent lateral breaking of the tie.

In molding the tie it is formed with widened portions 5 where the rails A are to be supported to give an enlarged bearing on 65 the ground as well as to strengthen the tie where the greatest strain comes.

The ends of the widened portions 5 are beveled as shown at 6 and provided with slots 7 to receive bolts 8 that are utilized to 70 engage the clamping members 9 that hold the rails secured to the tie, slots 7 extending the full thickness of the tie so that should the bolts break or become defective they may be renewed without disturbing the tie 75 or rails. The clamping members 9 are each formed with a shoulder 10 that engages the edges of the base of the rail and an elongated hole 11 to receive a clamping bolt 8.

As is well known, the grinding of the 80 wheel flanges on the inner sides of the rails gradually wears the rails off on the inner sides of the treads and unless counteracted in some manner the rails will become worn so badly as to be a source of danger. Ordinarily this wearing of the rails is counteracted by reversing the rails and then renewing them.

In my invention I provide a clamping mechanism by which the rails may be moved 90 toward the middle of the tie by degrees to counteract the wear on the treads of the rails consisting of a square washer 12 to engage the shoulder 10 on the clamping member 9, and formed with a bolt hole 13 95 that is not in the center of the washer but arranged at varying distances from its side edges.

In using my clamping members when the rails are first laid, the washers on the 100 clamping members on the inner sides of the rails are placed so that the edge farthest from the bolt hole 12 engage the shoulders 10, and the washers on the outer sides of the rails have the edges nearest the bolt 105 holes engaging the shoulders on the clamping members. As the rails are worn by the grinding of the wheel flanges the washers on the inner sides of the rails are readjusted so that the edges nearer the hole and of the 110 washers on the outer sides so that the edges farther from the hole are used in turn, thus

making four adjustments for each side of each rail or sixteen adjustments in all for the two rails. The elongated holes 11 in the members 9 admit of the sliding adjustment 5 of the members as just described.

14 indicates a wear plate between the rail A and tie 1.

Having thus described my invention what I claim is—

- 10 1. A railway tie having vertical slots in the sides thereof and opening laterally of said sides, and rail holding members removably and replaceably mounted in said slots.
- 15 2. A fastening for railway rails comprising an adjustable clamping member having a shoulder, engaging means for said clamping member, and a washer to engage said shoulder having an aperture therein to receive said engaging means that is unequally distant from the sides of the washer.
- 20 3. A fastening for railway rails comprising an adjustable clamping member having a shoulder, means to engage said clamping member, and a rectangular washer engaging said shoulder and having an aperture therein to receive said engaging means that is unequally distant from its sides.

4. A railway tie and rail fastening means comprising a tie having vertical slots in 30 the sides thereof and opening laterally of said sides, rail clamping members, and means to engage said clamping members, said engaging means being removably and replaceably mounted in said slots by being 35 moved laterally of the tie.

5. A railway tie and rail fastening means comprising a tie having vertical slots therein, rail clamping members having elongated holes therein, said clamping members having shoulders, bolts removably and replaceably mounted in said slots and engaging the holes in the clamping members, and rectangular washers engaging the shoulders on the clamping members, each of said washers having an aperture therein to receive the bolts aforesaid, said aperture being unequally distant from the sides of the washer.

In testimony whereof I hereto affix my 50 signature in the presence of two witnesses.

GARDNER A. BELKNAP.
